UNITED STATES PATENT OFFICE.

GEORGE N. BAKER, OF DECATUR, ILLINOIS.

METAL FRAME.

No. 911,195.

Specification of Letters Patent.

Patented Feb. 2, 1909.

Application filed June 3, 1908. Serial No. 436,481.

To all whom it may concern:

Be it known that I, GEORGE N. BAKER, a citizen of the United States, residing at Decatur, in the county of Macon, State of Illinois, have invented certain new and useful Improvements in Metal Frames, of which the following is a specification, reference being had to the accompanying drawings.

This invention relates to improvements in frames and particularly to frames designed for use in holding sections or pieces of wire-gauze, whereby a window screen is thereby formed.

I have illustrated my improved frame as a part of a window screen but it is to be understood that I do not restrict my invention to such use.

The object of my invention is to provide a frame that can be readily formed from a single strip of sheet metal and by reason of its novel construction will be exceedingly strong and rigid. I attain this object by the construction shown in the drawings and hereinafter specifically described.

That which I believe to be new will be pointed out in the claims.

In the accompanying drawings:—Figure 1 is a side elevation of my improved frame, and showing secured therein a section or piece of wire-gauze (partly broken away), the frame and gauze together thus forming a window screen. The screen shown is of that kind wherein two parts are employed together and are adjustable upon each other so as to fit windows of different widths. Fig. 2 is a vertical section taken at line 2—2 of Fig. 1. Fig. 3 is a cross-section taken at line 3—3 of Fig. 1. Fig. 4 is a detail, being a perspective view of a portion of the strip from which the frame is formed, showing the form assumed by the strip in the first part of the operation of forming a corner. Fig. 5 is a view similar to Fig. 3 and showing the form assumed by the strip upon the next operation in which the corner is completed. Fig. 6 is a view similar to Fig. 5, except that one of the bars of the frame has been given an additional longitudinal bend in order to produce a channel such as in the upper and lower bars of the complete frame that is shown in Fig. 1. Fig. 7 is a perspective view of a corner of the frame, the view being taken from the side opposite to that shown in Fig. 6. Fig. 8 is a view similar to that shown in Fig. 7 but taken in a different position. Fig. 9 is an enlarged detail, being

a cross-section taken at line 9—9 of Fig. 6. Fig. 10 is an enlarged detail, being a cross-section taken at line 10—10 of Fig. 6.

Referring to the several figures of the drawings, in which corresponding portions of the device are indicated by the same reference characters—A, B and C indicate, respectively, the upper, the end and the lower bars of the frame, said three bars being formed from a single strip of sheet metal.

The terms "upper", "end" and "lower" as herein used are merely for convenience of description, as it will of course be understood that what in one case would be properly described as an "upper" bar would in another case be differently termed.

In forming the frame, I take a strip of sheet-metal of suitable width and give to it at or near its longitudinal center a bend so that, as clearly shown in Fig. 4, there will be left a narrow space between the two thicknesses of material between which, at the proper time, the edges of the sheet of wire-gauze, if a window-screen is to be formed, can be inserted.

Referring now particularly to Fig. 4,—to form a corner of the frame, the doubled strip is given two edgewise bends as at a—a, such bending causing an outward bulging of the metal at two places in each thickness of the folded strip and producing at each side of the folded strip a pair of substantially triangular-shaped parts each of a double thickness of metal. The pair of triangular-shaped parts at one side of the folded strip are indicated by b and the pair on the opposite side by c. The edgewise bends imparted to the folded strip at a—a are of a degree to cause the folded strip to assume the shape of a device having two arms or branches d—e standing at right angles to each other, and which afterward become two of the sides of a right angled frame. These two arms or branches are separated by a doubled portion f, the upper edge of which must be at practically an angle of 45 degrees to the outer or folded edge of each of the arms or branches referred to. As shown in Fig. 4, the pair of doubled triangular parts b—b are bent or turned toward each other while the corresponding parts on the opposite side of the folded strip are bent or turned away from each other, and such parts are to be pressed down, as clearly shown in Fig. 5, so that one of the said pairs will lie against the portion f of the strip while

the other pair will lie against the arms or branches *d*—*e*.

While the arms or branches *d*—*e* are, by reason of the edgewise bending imparted to the folded strip at the points *a*—*a*, now at right angles to each other, it is evident that such arms or branches would not form satisfactory sides of a frame that was designed to completely fit within a rectangular opening,—as, for example, where the frame was intended for use as a window-screen frame,—for it is evident that at the corner of the window-opening there would be left a space between the inclined edge of the doubled portion *f* and the corner of the window-opening. The next step, however, in the operation of making the frame produces the desired sharp corner. Such step consists in bending each of the branches *d*—*e* longitudinally so as to produce on each of them a flange *g*. In thus bending the arms or branches to produce these flange portions, the triangular parts *b*—*b* and *c*—*c* are each necessarily bent also as well as the intermediate portion *f*. The lines upon which this bending to form the flanges *g*—*g* meet,—or nearly so,—is best shown in Figs. 5 and 6, and hence a sharp corner is formed adapted to correspond very closely to the sharp corner of an opening,—as a window-opening. By this construction, a corner for a right angled frame is formed without the necessity of disposing of the surplus metal, necessarily caused by edgewise bending, at the corner itself, which, in the actual construction of the frame, is a matter of some difficulty. By disposing of this surplus metal in the manner shown, whereby a portion of it appears at each side of the corner, the work of construction is rendered easier, a neater appearance is imparted, and a stronger device is formed than where all the surplus material is accumulated directly at the corner as in prior constructions. The manner of making all of the corners of a frame will be the same as that just described.

It is of course obvious that a four-sided frame can be made of a continuous strip, as described, although in Fig. 1 I have shown such continuous strip as forming but three sides of the frame, and that is for the reason that I have shown my invention embodied in a frame adapted to be used in connection with another similar frame which is to be slidingly connected with it. In the complete frame thus shown, the fourth bar of the frame is formed of a separate strip having its ends interfolded with the upper and lower bars *A* and *C*. This fourth bar is indicated by *D*, and it will be noted that it is located a little distance from the ends of the strip that forms the other bars *A*, *B* and *C*, so that there are left, as shown, two ends that extend beyond that portion of the frame that incloses the wire-gauze, such protruding

ends receiving and supporting other protruding ends on another correspondingly-shaped screen-frame.

In the construction shown, the flange portion *g* on the parts that constitute the upper and lower bars *A* and *C* is a little wider than the flange formed on the end bar *B* and is so made to permit these wider flanges to be turned or bent longitudinally to provide each with a supplemental flange *h*, as clearly shown in Fig. 6, thereby making each of the bars *A*—*C* of channel form, the better to adapt them to receive the upper and lower bars of another screen-section.

By the construction shown and described, I produce a very strong and rigid frame from a single strip of sheet-metal. By giving two edgewise bends as at *a*—*a* so as to bulge out the metal in the form of the two substantially triangular parts *b*—*b*, I produce two bars or sides of the frame that are disposed at right angles to each other and at the same time have the metal so disposed as to render it easy to longitudinally bend these arms or branches to form flanges for stiffening purposes, which bending, as has been shown, also produces a sharp and perfect corner, and at the same time such parts *b*—*b* form in connection with the intermediate portion *f* a very strong corner brace.

What I claim as my invention and desire to secure by Letters Patent is:—

1. A metal frame formed of a single strip, a corner of the frame being formed by two edgewise bends in the strip, a substantially-triangularly-shaped fold being formed at each of said bends, the frame bars that extend from said corner being each provided with a longitudinal flange, each flange extending through one of said folds.

2. A metal frame formed of a single strip, a corner of the frame being formed by two edgewise bends in the strip, a substantially-triangular-shaped fold being formed at each of said bends, the frame bars that extend from said corner being each provided with a longitudinal flange, the two flanges extending respectively through said folds and meeting between said bends.

3. A metal frame consisting of a strip bent longitudinally upon itself, a corner of the frame being formed by two edgewise bends in the strip, a substantially-triangular-shaped fold being formed at each of said bends, the frame bars that extend from said corner being each provided with a longitudinal flange, the two flanges meeting between said bends.

4. A metal frame formed of a single strip, a corner of the frame being formed by two edgewise bends in the strip, a substantially-triangular-shaped fold being formed at each of said bends, the frame bars that extend from said corner being each provided with a longitudinal flange, the two flanges

meeting between said bends, and one of said flanges being provided with a supplemental flange to form a channel in one of said bars.

5. A metal frame formed of a single strip folded longitudinally on itself, and having two edgewise bends, whereby the corner between two bars of the frame is formed, and two oppositely-located substantially-triangular-shaped folds at each of said bends, said 10 bars being each provided with a flange that extends through two of the said oppositely-located triangular-shaped folds.

6. A metal frame formed of a single strip folded longitudinally on itself, and having 15 two edgewise bends, whereby the corner be-

tween two bars of the frame is formed, and two oppositely-located substantially-triangular-shaped folds at each of said bends, said bars each being provided with a flange that extends through two of the said oppositely- 20 located triangular-shaped folds, said triangular-shaped folds on one face of the frame being bent toward each other and those on the opposite face being bent away from each other.
